EDOUARD VEDOVELLI, OF PARIS, FRANCE, ASSIGNOR TO LA SOCIETE LA METALLURGIQUE ELECTRIQUE, OF PARIS, FRANCE.

EXTRA-QUICK-ACTING CIRCUIT BREAKER

Application filed December 22, 1920. Serial No. 432,512.

To all whom it may concern:

Be it known that I, EDOUARD VEDOVELLI, citizen of the Republic of France, and resident of Paris, France, post-office address 4 5 Rue de Naples, have invented new and useful Extra-Quick-Acting Circuit Breakers, which improvements are fully set forth in the following specification.

This invention relates to a switch so constructed as to act automatically and very quickly when the current in the circuit acquires an excessive strength.

In order to make the following explanation as clear as possible, the accompanying drawing shows by way of example a construction of the extra quick circuit-breaker according to the invention.

Figure 1 is a diagrammatic view showing the apparatus closed.

Figure 2 shows the part enabling the apparatus to be re-set ready for working again and producing the opening.

Figure 3 shows the position of the movable part after it has been moved owing to an excess of current.

Figure 4 shows the position of the movable part after the springs have been cocked.

Figure 5 is a detail view showing the use of a series of helical springs for the movable part.

Figure 6 shows the same arrangement with spring blades.

Figure 7 shows an extra quick movable part with two contacts which are represented as closed.

Figure 8 is a view generally similar to Figure 7 but showing the two contacts open.

Figure 9 shows the position of the parts after the final break.

Figure 10 relates to a modified construction of the device balancing the direct pull of the springs.

As will be seen from Figure 1, the current is admitted at 1, passes into the winding 2 of a large electromagnet, the armature of which is marked 3, passes to the spindle 4 of a movable lever 5, passes through said lever into a conductor part 6 which is fixed or almost fixed, as it merely has the flexibility required to ensure a thorough contact, and then passes through a movable contact 7 from which it escapes at the hooked end 8.

The movable part 7 is made as light as possible and is pulled endwise in one direc-

tion, toward the right in this instance, by 55 powerful springs 9, 10, but is normally held in place by a pawl 11.

The weight of the movable part 7 and the power of the springs 9, 10 are calculated so that when the pawl 11 is disengaged, the 60 part will move with the desired speed. In order to avoid the shock that would take place at the end of the travel of said part the springs are arranged so that they form at the same time shock-absorbers, the point 65 of attachment of the springs to the movable part passing, owing to the momentum of the part, beyond the position in which the attraction is zero. A pawl 12 engages with the hooked end 8 of the movable part 7 after 70 it has completed its travel and thus prevents it from assuming, under the action of the springs, a vibratory motion.

The pawl 11 engages with the nose 13 of a lever 15 which is pivoted intermediate 75 its ends at 14, as shown. This lever is pulled against a stop 18 by a powerful spring 16, but is caused to turn in one direction under the action of the pawl 11 carried by the movable member 7.

The lever 15 can be moved by the action of the armature 3 of the electromagnet by means of any suitable gear. In the drawing, the end of said lever opposite to the nose 13 is connected by a link 17 to the adjacent 85 end of a lever 19 which is pivoted intermediate its ends on a pin 20 and has its lower arm connected by a link 22 to said armature. It will be understood that for a certain strength of current there will be a dynamic equilibrium between the forces acting together; on the one hand, the positive force of the springs 9, 10, and on the other hand the negative forces which are added together, of the spring 16 and of the electromagnet.

At the contacts 6, 7 terminate the ends of a circuit comprising a resistance 23 and a solenoid 24, the object of which is to bring about the movement of the lever 5.

To that end, the lever 5 is connected by a rod 25 to the centre of a balance beam 26, or any other differential mechanism such that the said connecting rod 25 can be moved by the action of two different mechanical movements, said beam having the tendency to move the lever in question away from the contact 6. One end of the beam 26 has con-

nected to it a retractile spring 32 which tends to move it away from a pair of spaced stops 27, and said end is connected at the opposite side from the spring to a hand lever 31 by a rod 29. In operating, this connecting rod acts on the end of the balance beam to which it is connected, and if it is assumed that the other end is fixed, the movement of the rod will swing the beam counter-clockwise, and said beam, in turn, will rock lever 5 counter-clockwise, its upper arm moving away from the contact 6. The movement of the rod 29 is controlled by a locking pawl 33 which is designed for engagement with a projection or finger 30 on the hand lever 31 and which, when so engaged, prevents the operation of said lever and said spring 32 and, consequently, the movement of the rod. The pawl or detent 33 is acted on by the solenoid 24 included in the shunt circuit.

The other end of the balance beam 26 may, as shown, be operatively connected, by means of a rod or link 21 for example, to the lever 19 which carries the armature 3, so that when the armature is shifted, its movements will be transmitted, through the parts 22, 19 and 21 to the balance beam.

The working of the apparatus will substantially be as follows:

If the strength of current is zero or below a certain limit, the parts above described will remain at rest in the position illustrated in Figure 1; but when such limit is reached, then the attraction exercised on the armature 3 will be sufficient to start the movement of the latter. The ratios of the levers and the constructive dimensions are such that for an infinitely small movement of the armature 3, there will be a release of the pawl 11. The movable contact member 7 will then move with all the speed desired.

At that moment the resistance 23 and the solenoid 24 are suddenly switched into the circuit, a limitation of the current strength then taking place, which depends on the ohmic value given to the resistance 23. The mass of the armature 3 being comparatively large, the armature 3 takes much longer time to move than the part 7 and the latter will have completed its travel while the armature 3 will be still moving.

This movement of the armature will be transmitted through the rod 21 to the balance beam which will begin to swing the lever 5 into open position; but a very short time afterwards, a current will be passing through the solenoid 24 inserted into the circuit of the resistance, in order to bring about the release of the spring 32, and the other end of the balance beam will add its speed in order to produce the opening of the lever 5, the intermediate contact 6 remaining fixed.

Owing to this arrangement, it will be possible by a judicious regulation of the position of the core of the solenoid 24 and of its

number of ampere windings, to obtain an apparatus which will completely open the circuit only when the short-circuit is a fairly violent one.

In fact, the value of the current passing through the resistance, depends on the resistance of the outer circuit. In this case of course the connecting rod 29 and the balance beam would be done away with, the spring 32 being left alone to act on the opening lever 5.

As soon as the opening has been effected by the action of the short-circuit established, the closing will be effected by acting by hand on the lever 31 and by moving by any desired means the movable part 7. The springs 9, 10 could be cocked either by hand, by means of a lever gear, or by a screw or by any suitable electromagnet, and for the manipulation in question the action of the handle 31 might be utilized.

It must be pointed out that the extra quick part 7 such as it has been described, has been provided for inserting the resistance; but it could equally well be used for producing the opening. In the same way, two identical parts could be used, working together or in cascade, one for introducing the resistance, and the other for producing the opening. This working of the former would result in the working of the second. As has been seen, helical springs have been diagrammatically indicated for driving the movable part 7 like the arrow of a bow, and a pawl has been provided for stopping the said part as soon as its travel has been completed.

A practical means for re-setting the movable part ready for subsequent working, will now be considered.

To that end, the proceeding is as follows: The points of reaction of the springs 9, 10 are arranged on a movable frame 1', 2', 3' which can slide in the same direction as the movable part under the action of a lever, cam or any other device whose action can be multiplied by means of a handle.

Figure 2 shows the movable part ready to move in the direction of the arrow 5' to produce the circuit-opening action, but being held back by the pawl 11.

If owing to an excess of current, the apparatus becomes operative, the pawl 11 will be released, the movable part will assume the position shown in Figure 3, and the pawl 7' will prevent said part from returning in the direction of the arrow 8'; but the angle β between the springs is greater than the angle α of the first case, and therefore if the pawl 7' is released at that moment, the movable part will not return to the position in Figure 2.

At this moment, the movable frame is moved by means of the handle 4' (Figure 4) in such a manner as to cock the springs

and cause them to form an angle α' sufficient and less than the angle α . The result of this movement of the frame will be that when the tension is sufficient, the pawl 7' 5 will be disengaged by means of a finger 9'. The movable part will start moving in the opposite direction, and will pass slightly beyond the normal position and engage with the pawl 11. By returning the handle 4' to the position shown in Figure 2, 10 the springs will be given again the desired tension for a new release.

The construction of a spring part capable of exerting the desired forces without 15 introducing at the same time a great momentum, requires certain precautions. To that end, the spring means may comprise as many springs of the smallest possible dimensions as will be required, as shown in 20 Figure 5, and in place of the helical springs, could be used spring blades as indicated in Figure 6. The ends of the blades would pass in this case over rollers so as to reduce the friction.

25 In the arrangement illustrated in Figure 1 has been shown the path of the current such that the ultra quick part must be connected to the main circuit and to the resistance, for instance by means of flexible 30 connections. These connections might introduce inertia and resistances difficult to calculate; to obviate the said drawback and at the same time to double the speed of 35 opening, the following arrangement has been made:

The opening parts such as described, have been duplicated, 15' and 10' representing 40 ultra quick parts which work together under the action of parts such as have been described. It is in reality one part carrying 45 two contacts 11' and 12'. In Figure 7 which is a plan, the current enters through 13' and escapes at 14'.

In Figure 8, the extra quick acting part 45 has been moved away, and the current passes through the resistances, 16' and 17' being fixed contacts. In Figure 9, the final 50 opening has taken place between the parts 16' and 18' on the one hand, and 17' and 19' on the other hand, 18' and 19' being movable levers.

In the construction Figure 1, for the purpose of balancing the direct pull of the 55 springs acting on the extra quick part, is shown a pawl device 11 acting on a lever 13. This device has for its sole object to transmit the static equilibrium effort to the spindle of the said lever. It goes without saying that this device could be replaced by 60 any similar one giving the same results, for instance the following one which has the same characteristics:

Let it be assumed that 28' 20' is the extra 65 quick acting movable part, Figure 10, having the tendency to move in the direction of

the arrow 21'. At the end of the part is provided a rack or cam face 22' pressing against a roller 23' supported on the end of a lever 24 rotatable about a spindle 24'. The position of the cam face gives the roller 70 a reaction in the direction of the arrow 25'; by suitably adjusting the inclination the reaction on the axis 24' in the direction of the arrow could be as small as desired and also as great as desired. This spindle 75 24' plays the part of the spindle 14 of Figure 1.

A spring 26' prevents the lever 24 from moving, and holds it in engagement with a stop 27', this spring playing the same part 80 as the spring 16 of Figure 1, so that a very slight effort, whether positive or negative, is required for holding or moving the lever 24.

I claim as my invention:

1. In a quick-acting, circuit-breaking mechanism, the combination of a fixed contact; a movable contact element cooperative therewith; springs tending to move said contact element away from the fixed contact; a detent for holding said contact element against such movement; an electromagnet for releasing said detent; a second movable contact element cooperative with the fixed contact; a circuit, wherein both 95 contact elements and the magnet are included; and means controlled by said magnet for moving the second contact element away from the fixed contact.

2. In a quick-acting, circuit-breaking 100 mechanism, the combination of a fixed contact; a pair of movable contact elements disposed at opposite sides of and normally engaged with the fixed contact; a circuit wherein both contact elements are included; 105 a magnet in said circuit; spring means tending to move one of the contact elements away from the fixed contact; means for holding said contact element against such movement; means controlled by the magnet 110 for releasing said holding means to permit the movement of said contact element; and means acting to automatically move the other contact element away from the fixed contact after the movement of the first contact element has commenced.

3. In a quick-acting, circuit-breaking mechanism, the combination of a fixed contact; a pair of movable contact elements disposed at opposite sides of and normally 120 engaged with the fixed contact; a circuit wherein both contact elements are included; a magnet in said circuit; spring means tending to move one of the contact elements away from the fixed contact; means for holding 125 said contact element against such movement; means controlled by the magnet for releasing said holding means to permit the movement of said contact element; means for moving the other contact element away 130

from the fixed contact; means for locking the last-named means against operation; and means for releasing said locking means.

4. In a quick - acting, circuit - breaking mechanism, the combination of a fixed contact; a pair of movable contact elements disposed at opposite sides of and normally engaged with the fixed contact; a circuit wherein both contact elements are included; 10 a magnet in said circuit; spring means tending to move one of the contact elements away from the fixed contact; means for holding said contact element against such movement; means controlled by the magnet for 15 releasing said holding means to permit the movement of said contact element; means for moving the other contact element away from the fixed contact; a catch for locking the last-named means against operation; 20 and electro-magnetic means for releasing said catch.

5. In a quick - acting, circuit - breaking mechanism, the combination of a fixed contact; a pair of movable contact elements 25 disposed at opposite sides of and normally engaged with the fixed contact; a circuit wherein both contact elements are included; a magnet in said circuit; spring means tending to move one of the contact elements away 30 from the fixed contact; means for holding said contact element against such movement; means controlled by the magnet for releasing said holding means to permit the movement of said contact element; means 35 for moving the other contact element away from the fixed contact; a catch for holding the last-named means against operation; a solenoid for releasing said catch; and means for establishing a short circuit through the 40 solenoid after the movement of the first contact element has commenced.

6. In a quick - acting, circuit - breaking mechanism, the combination of a fixed contact; a pair of movable contact elements dis-

posed at opposite sides of and normally engaged with the fixed contact; a circuit wherein both contact elements are included; a magnet in said circuit; spring means tending to move one of the contact elements away from the fixed contact; means for holding 45 said contact element against such movement; means controlled by the magnet for releasing said holding means to permit the movement of said contact element; a balance beam connected to the other contact 50 element for moving the same away from the fixed element; and means for automatically operating said beam after the movement of the first contact element has commenced.

7. In a quick - acting, circuit - breaking mechanism, the combination of a fixed contact; a pair of movable contact elements disposed at opposite sides of and normally engaged with the fixed contact; a circuit wherein both contact elements are included; 60 a magnet in said circuit; spring means tending to move one of the contact elements away from the fixed contact; means for holding said contact element against such movement; means controlled by the magnet for releasing 65 said holding means to permit the movement of said contact element; a balance beam connected to the other contact element for moving the same away from the fixed element; a catch normally locking the beam 70 against operation; means for operating said beam when unlocked; and means for automatically releasing the catch after the movement of the first contact element has commenced. 80

In testimony whereof I have signed this specification in the presence of two subscribing witnesses.

EDOUARD VEDOVELLI.
